CLAIM

The ornamental design for a combined cosmetic container and applicator cap, as shown and described.

DESCRIPTION

FIG. 1 is a side elevational view of a combined cosmetic container and applicator cap showing our new design; FIG. 2 is a side elevational view of the applicator cap; FIG. 3 is a front elevational view thereof; FIG. 4 is a rear elevational view thereof; FIG. 5 is a front elevational view of the cap in alternate position;

FIG. 6 is a top plan view of the cap with tip removed for ease of illustration;

FIG. 7 is a bottom plan view thereof;

FIG. 8 is a top plan view of an applicator cap showing another modified form of our new design;

FIG. 9 is a top plan view of an applicator cap showing another modified form of our new design;

FIG. 10 is a side elevational view of the cosmetic container;

FIG. 11 is a top plan view thereof;

FIG. 12 is a bottom plan view thereof; and

FIG. 13 is a top plan view on an enlarged scale of the applicator cap partially withdrawn from the container and pivoted to horizontal orientation.
